UNITED STATES PATENT OFFICE.

ELLIS F. FROST, OF WASHINGTON, DISTRICT OF COLUMBIA.

ELECTRIC ACTION FOR ORGANS.

1,243,280.

Specification of Letters Patent.

Patented Oct. 16, 1917.

Application filed November 15, 1915. Serial No. 61,684.

To all whom it may concern:

Be it known that I, ELLIS F. FROST, a citizen of the United States, and resident of Washington, D. C., have invented certain new and useful Improvements in Electric Actions for Organs, of which the following is a full, clear, and exact specification.

My invention relates to electric actions for organs.

10 The object of my invention is the production of a novel, useful, and feasible electric organ-action of the general type disclosed in my Patent No. 1,228,899, issued June 5, 1917, whereby it is made possible to play 15 the registers of organ pipes on each of a number of keyboards in any combination of the registers or in any combination of any of the registers in any desired relative musical transposition thereof as fully set 20 out in this specification and illustrated in the accompanying drawing in which Figure 1 is a diagrammatic representation of the parts employed and the circuits therefor, Fig. 2 is a side view of a portion of a register switch-pin-carrying rod, and Fig. 3 is 25 a side view of a multiple contact key switch.

Of the reference characters used, A to G inclusive, whether upper or lower case or however modified by sharps or flats, refer 30 to relative position in the musical scale.

Referring to Fig. 1, 1, 1', 1'', represent three pipes of a register as for instance a salicional, and 2, 2', 2'', represent three pipes of another register as for instance a 35 gedackt.

For convenience in description pipes 1 and 2 are supposed to be of the pitch of the tenor C of the musical scale, 1' and 2' an octave above or of the pitch of middle C, 40 and 1'' 2'' an octave higher still or of the pitch of soprano C''.

3, 4, 5, 6, 7, 8, represent electro-magnetic devices designed when energized to operate respectively pipes 1, 1', 1'', 2, 2', 2''. The 45 short lines C#, D, F, A, &c., represent the attachment of leads to electro-magnetic devices intermediate in the octave between those shown. The wind chest and operating valves intermediate between the electro-magnetic devices and pipes are not shown. 50 9 represents a battery from one terminal of which extend conductors 10 and 11 and from the other terminal conductor 12. M¹ to M⁶, N¹ to N⁶ represent rods of non-con-

ducting material. Each rod carries as many 55 conducting pins as there are keys in a keyboard, only three pins on each rod being shown, those of each rod being designated by the letters o, p, q. Pairs of contact springs are in juxtaposition to each pin and in such 60 relation that when a rod is moved so as to carry its pins toward the springs the pins will engage the springs and bridge them and when moved in the opposite direction the pins will leave the springs unbridged. 65 Contact pins o, p, q, with their respective contact springs will hereafter be named register switches.

Fig. 2 shows a side view of a portion of a pin carrying rod, as rod M¹, thirteen pins 70 being shown, this being the number required to the octave. If the first pin to the left of Fig. 2 be assigned to the tenor C this pin will correspond to one of the o pins of Fig. 1 the other pins filling the octave to middle 75 o to which pin p corresponds in Fig. 1 and Fig. 2. A pair of contact springs in relation to the o pin is shown in Fig. 2 there being a separate pair (not shown) for each pin.

M⁷, M⁸, M⁹, N⁷, N⁸, N⁹, represent conducting bars each carrying contact pins r, s, t, u, v, w, a side view being shown in Fig. 3 with a contact spring for the pin u. Bars M⁷ to M⁹, N⁷ to N⁹ with their contact pins 85 and respective contact springs will hereafter be named key switches.

Rods M¹ to M⁶, N¹ to N⁶, are controlled by drawstops one for each rod either directly or through intermediate means, that 90 shown being electro-magnetic, the electro-magnets respectively allotted to the rods M¹ to M⁶, N¹ to N⁶ being M¹⁰ to M¹⁵, N¹⁰ to N¹⁵.

M¹⁰ to M²¹ and N¹⁰ to N²¹ represent draw- 95 stops associated with each of which is a pair of contact springs held out of contact by the drawstop when the drawstop is in the "in" position and allowed to make contact when the drawstop is in the "out" position.

Key switches M⁷, M⁸, M⁹, N⁷, N⁸, N⁹, are respectively in operative relation to electro-magnets M²², M²³, M²⁴, N²², N²³, N²⁴.

K, K', K'', represent three keys of a keyboard and L, L', L'', three keys of another keyboard, those of each keyboard shown being respectively of the position in the mu-

sical scale indicated by the letters C, c, c', being that of the pipes shown.

Associated with each key is a pair of contact springs designed to be out of contact 5 when the key is at rest and to be brought into contact when the key is operated.

The various parts are connected as follows:

3, 4, 5, 6, 7, 8, are connected in parallel 10 to the conductor 10. 3 is connected to one contact spring of the pair associated with contact pins o of rods M¹, M², M³, and also with one contact spring of each pair associated with contact pins o of rods N¹, N², N³. 15 4 is connected with one contact spring of each pair associated with contact pins p of rods M¹, M², M³, and also with one contact spring of each pair associated with contact pins p of rods N¹, N², N³. 5 is connected 20 with one contact spring of each pair associated with contact pins q of rods M¹, M², M³, and also with one contact spring of each pair associated with contact pins q of rods N¹, N², N³. 6 is connected 25 with one contact spring of each pair associated with contact pins o of rods M⁴, M⁵, M⁶, and with one contact spring of each pair associated with pins o of rods N⁴, N⁵, N⁶. 7 is connected with one contact spring 30 of each pair associated with contact pins p of rods M⁴, M⁵, M⁶, and with one contact spring of each pair associated with contact pins p of rods N⁴, N⁵, N⁶. 8 is connected 35 with one contact spring of each pair associated with contact pins q of rods M⁴, M⁵, M⁶, and with one contact spring of each pair associated with contact pins q of rods N⁴, N⁵, N⁶.

Of the other contact springs of the pairs 40 associated with pins o of rods M¹, M², N¹, N², that associated with pin o of rod M¹ is connected with the contact spring associated with pin t of M¹, that associated with pin o of rod M² is connected with the 45 contact spring associated with pin r of M², that associated with pin o of rod N¹ is connected with the contact spring associated with pin t of N¹ and that associated with pin o of rod N² is connected with the contact spring associated with pin r of N².

Of the other contact springs of the pairs 50 associated with pins o of rods M⁴, M⁵, and N⁴, N⁵, that associated with pin o of rod M⁴ is connected with the contact spring 55 associated with pin u of M⁴, that associated with pin o of rod M⁵ is connected with the contact spring associated with pin s of M⁵, that associated with pin o of rod N⁴ is connected with the contact spring 60 associated with pin u of N⁴, and that associated with pin o of rod N⁵ is connected with the contact spring associated with pin s of N⁵.

Of the other contact springs of the pairs

associated with pins p of rods M¹, M², M³, 65 and N¹, N², N³, that associated with pin p of rod M³ is connected with the contact spring associated with pin v of M⁷, that associated with pin p of rod M¹ is connected with the contact spring associated with pin 70 t of M⁸, that associated with pin p of rod M² is connected with the contact spring associated with pin r of M⁹, that associated with pin p of rod N³ is connected with the contact spring associated with pin v of N⁷, that associated with pin p of rod N¹ is connected with the contact spring associated with pin t of N⁸, and that associated with pins p of rod N² is connected with the contact spring associated with pin r of N⁹. 75

Of the other contact springs of the pairs associated with the pins p of the rods M⁴, M⁵, M⁶, and N⁴, N⁵, N⁶, that associated with pin p of rod N² is connected with the contact spring associated with pin v of N⁷, that associated with pin p of rod N¹ is connected with the contact spring associated with pin t of N⁸, that associated with pin p of rod M⁴ is connected with the contact spring associated with pin t of M⁷, 80 that associated with pin p of rod M⁵ is connected with the contact spring associated with pin u of M⁸, that associated with pin p of rod M⁶ is connected with the contact spring associated with pin s of M⁹, that associated with pin p of rod N⁶ is connected with the contact spring associated with pin t of N⁷, that associated with pin p of rod N⁴ is connected with the contact spring associated with pin u of N⁸, and that associated with pin p of rod N⁵ is connected with the contact spring associated with pin s of N⁹. 85

Of the other contact springs of the pairs associated with the pins q of the rods M¹, M², N¹, N², that associated with pin q of rod M³ is connected with the contact spring associated with pin v of M⁸, that associated with pin q of rod M¹ is connected with the contact spring associated with pin t of M⁹, that associated with pin q of rod N³ is connected with the contact spring associated with pin v of N⁸, and that associated with pin q of rod N¹ is connected with the contact spring associated with pin t of N⁹. 90

Of the other contact springs of the pairs associated with pins q of the rods M⁴, M⁵, and N⁴, N⁵, that associated with pin q of rod M⁶ is connected with the contact spring associated with pin w of M⁸, that associated with pin q of rod M⁴ is connected with the contact spring associated with pin u of M⁹, that associated with pin q of rod N⁶ is connected with the contact spring associated with pin w of N⁸, and that associated with pin q of rod N⁴ is connected with the contact spring associated with pin u of N⁹. 95

It is to be noted that each electro-magnetic device of a register is included in a branch circuit controlled by keys in each keyboard in unison, suboctave, and superoctave pitch relation to said device. 100

Electro-magnets M¹⁰ to M¹⁵ are connected

in parallel to the conductor 12. Electro-magnet M^{10} is also connected to one of the contact springs of the pair associated with drawstop M^{17} . Electro-magnet M^{11} is also connected with one of the contact springs of the pair associated with drawstop M^{19} . Electro-magnet M^{12} is also connected with one of the contact springs of the pair associated with drawstop M^{18} . Electro-magnet M^{13} is also connected with one of the contact springs of the pair associated with drawstop M^{20} . Electro-magnet M^{14} is also connected with one of the contact springs of the pair associated with drawstop M^{19} .
 10 M^{15} is also connected with one of the contact springs of the pair associated with drawstop M^{21} . The other contact springs of the pairs associated with drawstops M^{16} to M^{21} are connected to the 20 conductor 11.

Electro-magnets N^{10} to N^{15} are connected in parallel with the conductor 12. Electro-magnet N^{10} is also connected with one of the contact springs of the pair associated with 25 drawstop N^{17} . Electro-magnet N^{11} is also connected with one of the contact springs of the pair associated with drawstop N^{16} . Electro-magnet N^{12} is also connected with one of the contact springs of the pair associated with drawstop N^{18} . Electro-magnet N^{13} is also connected with one of the contact 30 springs of the pair associated with drawstop N^{20} . Electro-magnet N^{14} is also connected with one of the contact springs of the pair associated with drawstop N^{19} . Electro-magnet N^{15} is also connected with one of the contact springs of the pair associated with drawstop N^{21} . The other contact 35 springs of the pairs associated with the drawstops N^{16} to N^{21} are connected to the conductor 11.

Electro-magnets M^{22} , M^{23} , M^{24} , are connected in parallel with the conductor 11. Electro-magnet M^{22} is also connected with 45 one of the contact springs of the pair associated with the key K. Electro-magnet M^{23} is also connected with one of the contact springs of the pair associated with the key K'. Electro-magnet M^{24} is also connected 50 with one of the contact springs of the pair associated with the key K''. The other contact springs of the pairs associated with the keys K, K', K'', are connected with conductor 12.

55 Electro-magnets N^{22} , N^{23} , N^{24} , are connected in parallel with conductor 11. Electro-magnet N^{22} is also connected with one of the contact springs of the pair associated with the key L. Electro-magnet N^{23} is also 60 connected with one of the contact springs of the pair associated with the key L'. Electro-magnet N^{24} is also connected with one of the contact springs of the pair associated with the key L''. The other contact springs

of the pairs associated with the keys L, L', 65 L''; are connected with conductor 12.

The several parts may be operated against any desirable restoring means.

The arrangement described and shown 70 posits three drawstop controlled rods for each register for each keyboard so that for ten registers and two manual keyboards there would be sixty drawstop controlled rods. For a pedal keyboard there would be but one or two rods per register making the 75 total number of draw-stop controlled rods and therefore the number of drawstops for the ten registers seventy to eighty to which must be added the drawstop controlled rods of pedal pipes one rod for each register of 80 pedal pipes. For the four foot and two foot scale registers practical considerations would require but one drawstop controlled rod for each register per keyboard. Thus for each eight foot scale register there will 85 be three drawstops of sixteen foot, eight foot, and four foot denomination respectively for each manual keyboard. There will be as many register switches operated by each drawstop controlled rod as there are 90 keys per keyboard, namely, sixty one for those rods related to the manual keyboards and about thirty two for those drawstop controlled rods related to the pedal keyboard. 95

Each keyswitch M^7 , M^8 , &c. requires as many pins r , s , t , &c., as there are drawstop controlled rods M^1 , M^2 &c., related to the manual controlling the key switch M^7 , or M^8 , &c., so that ten registers require thirty pins 100 for each key switch, the pedal key switches requiring a less number of pins.

When there are but sixty one pipes in a register the suboctave and superoctave connections are carried out only within the compass of the register. Also, since each pipe 105 controlling device is, so far as the scheme is concerned, to be connected to a key switch in suboctave and superoctave relation the scheme can only be carried out within the 110 compass of the keyboards.

Since the pipes of a register as well as the keys of a keyboard are commonly designated by terms denoting relative pitch in the musical scale it is appropriate to designate the pipe sounding devices and also the branch circuits including the keys of a keyboard and the pipes of a register in the unison, suboctave, and superoctave relation, 115 as unison, suboctave, and superoctave devices and circuits respectively. It is for the sake of clearness and the avoidance of a tedious circumlocution that the devices and circuits are so designated in the claims. 120

It is to be especially noted that the branch 125 circuits extending from the key switches to the pipe sounding devices form similar groups of circuits, the group from each key

switch comprising a unison, a suboctave, and a superoctave circuit; also that the circuits extending from the pipe sounding devices to the key switches form similar groups of circuits the group from each pipe sounding device comprising a unison, a suboctave, and a superoctave circuit; and that, of the groups of circuits from a key and a device of the same pitch the unison circuit is alone 10 identical in both groups.

While the switches consisting of contact springs closed and opened by pins controlled by drawstops might be designated drawstop controlled switches, it is preferable for the 15 purpose of clarity in the claims to designate them register switches since their operation determines what register at a given pitch relation shall be related to a given keyboard.

20 While each circuit related with a key switch is separately closed and opened upon the operation of the key controlling that key switch yet the various spring contacts and their respectively associated pin contacts constitute a multiple contact switch each spring contact being individual to a circuit and the pins by reason of their being connected together by the bar supporting them being common to all the circuits. In 25 fact, the spring contacts might be made to contact directly with the bar this then becoming the common contact.

The operation of my invention is as follows:

30 When no drawstops are drawn and no keys are operated no circuits are closed. When no drawstops are drawn the operation of any key closes only the circuit through the electro-magnet with which it is associated and therefore operation of the key switches serves no function. When no keys are operated operation of the drawstops only closes circuits through the electro-magnets with which they are associated and 35 therefore operation of the register switches serves no function.

If drawstop M^{17} alone be drawn a circuit is closed through electro-magnet M^{10} and the register switches o, p, q , of rod M^1 are closed. If, now, key K be operated a circuit is closed through electro-magnet M^{22} and the pin t of key switch M^1 being thus brought into contact with its associated contact spring a circuit is also closed as 40 follows, battery 9, conductor 10, electro-magnet 3, register switch o of rod M^1 , contact spring and associated contact pin t of key switch M^1 , conductor 12, to battery, and pipe 1' is sounded, it being of unison pitch with the key K . Operation of key K' while drawstop M^{17} alone is drawn closes a circuit through electro-magnet M^{23} operating key switch M^8 and bringing its contact pin t into contact with its associated contact spring thus closing a circuit as follows, battery 9, conductor 10, electro-magnet 4, register switch p of rod M^1 , contact spring and associated contact pin t of key switch M^8 , conductor 12, to battery, and pipe 1' is sounded, it being of unison pitch with the key K' . Operation of key K'' while drawstop M^{17} alone is drawn closes a circuit through electro-magnet M^{24} operating key switch M^9 , bringing its contact pin t into contact with its associated contact spring thus closing a circuit as follows, battery 9, conductor 10, electro-magnet 5, register switch q of rod M^1 , contact spring and associated contact pin t of key switch M^9 , conductor 12, to battery, and pipe 1'' is sounded, it being of unison pitch with the key K'' .

If drawstop N^{17} alone be drawn a circuit is closed through the electro-magnet N^{10} and the register switches o, p, q , of rod N^1 are closed. If, now, key L be operated a circuit is closed through electro-magnet N^{22} and the contact pin t of key switch N^7 being thus brought into contact with its associated contact spring a circuit is closed as follows, battery 9, conductor 10, electro-magnet 3, register switch o of rod N^1 , contact spring and associated contact pin t of key switch N^7 , conductor 12, to battery, and pipe 1 is sounded, it being of unison pitch with the key L . Operation of key L' while drawstop N^{17} alone is drawn closes a circuit through electro-magnet N^{23} , operating key switch N^8 and bringing its contact pin t into contact with its associated contact spring thus closing a circuit as follows, battery 9, conductor 10, electro-magnet 4, register switch p of rod N^1 , contact spring and associated contact pin t of key switch N^8 , conductor 12, to battery, and pipe 1' is sounded, it being of unison pitch with the key L' . Operation of key L'' while drawstop N^{17} alone is drawn closes a circuit through electro-magnet N^{24} operating key switch N^9 , bringing its contact pin t into contact with its associated contact spring thus closing a circuit as follows, battery 9, conductor 10, electro-magnet 5, register switch q of rod N^1 , contact spring and associated contact pin t of key switch N^9 , conductor 12, to battery, and pipe 1'' is sounded, it being of unison pitch with the key L'' .

If drawstop M^{20} alone be drawn operation of key K will cause pipe 2 to sound; operation of key K' will cause pipe 2' to sound; operation of key K'' will cause pipe 2'' to sound; these pipes thus being sounded in unison with the keys. The circuits involved can be readily traced by one skilled in the art. If drawstop N^{20} alone be drawn operation of key L will cause pipe 2 to

thus the pipes of the first register may be sounded in the unison by operating the keys of either or both keyboards.

If drawstop M^{20} alone be drawn operation of key K will cause pipe 2 to sound; operation of key K' will cause pipe 2' to sound; operation of key K'' will cause pipe 2'' to sound; these pipes thus being sounded in unison with the keys. The circuits involved can be readily traced by one skilled in the art. If drawstop N^{20} alone be drawn operation of key L will cause pipe 2 to

- sound; operation of key L' will cause pipe $2'$ to sound; operation of key L'' will cause pipe $2''$ to sound; these pipes thus being sounded in unison with the keys. The circuits involved can be readily traced by one skilled in the art. Thus the pipes of the second register may be sounded in the unison by operating the keys of either or both keyboards.
- 10 Thus the pipes of either or both registers may be sounded in the unison by operating the keys of either or both keyboards.
- The circuits involved in the above operations are denominated unison circuits.
- 15 If drawstop M^{18} alone be drawn, rod M^2 is operated and the register switches o, p, q , of rod M^2 are closed. If, now, key K be operated the key switch M^1 will be operated and its contact pin r will be brought into contact with its associated contact spring which is unconnected in the drawing. Operation of key K' while drawstop M^{18} alone is drawn operates key switch M^8 its contact pin r being brought into contact with its associated contact spring thus closing a circuit as follows, battery 9, conductor 10, electro-magnet 3, register switch o of rod M^2 , contact spring and associated contact pin r of key switch M^8 , conductor 12, to battery, and pipe 1 is sounded, it being of pitch an octave below that of key K' . Operation of key K'' while drawstop M^{18} alone is drawn operates key switch M^8 its contact pin r being brought into contact with its associated contact spring thus closing a circuit as follows, battery 9, conductor 10, electro-magnet 4, register switch p of rod M^2 , contact spring and associated contact pin r of key switch M^8 , conductor 12, to battery, and pipe 1' is sounded, it being of pitch an octave below that of the key K'' .
- If drawstop N^{18} alone be drawn, operation of key L' will cause pipe 1 to sound, it being in pitch an octave below that of key L' ; and operation of key L'' will cause pipe 1' to sound it being in pitch an octave below that of key L'' , the relation of the movable and fixed parts and the circuits being similar to those described above and readily traceable to one skilled in the art.
- Thus the pipes of the first register in their suboctave relation may be sounded by operation of keys of either or both keyboards.
- 55 If drawstop M^{19} alone be drawn, operation of key K' will cause pipe 2 to sound it being of pitch an octave below that of key K' ; operation of key K'' will cause pipe 2' to sound it being of pitch an octave below that of key K'' , the circuits being readily traceable.
- If drawstop N^{19} alone be drawn, operation of key L' will cause pipe 2 to sound it being of pitch an octave below that of key L' ; operation of key L'' will cause pipe 2' to sound it being of pitch an octave below that of key L'' , the circuits being readily traceable.
- Thus the pipes of the second register in their suboctave relation may be sounded by the operation of keys of either or both keyboards.
- 70 Thus the pipes of either or both registers in their suboctave relation may be sounded by the operation of keys of either or both keyboards.
- The circuits involved in the above operations are denominated suboctave circuits.
- 75 If drawstop M^3 alone be drawn, rod M^3 is operated and its register switches o, p, q , are closed. If, now, key K be operated the key switch M^1 will be operated and its contact pin v will be brought into contact with its associated contact spring thus closing a circuit as follows, battery 9, conductor 10, electro-magnet 4, register switch p of rod M^3 , contact spring and associated contact pin v of key switch M^1 , conductor 12, to battery, and pipe 1' is sounded, it being of pitch an octave above that of the key K . Operation of key K' while drawstop M^3 alone is drawn operates key switch M^8 its contact pin v being brought into contact with its associated contact spring thus closing a circuit as follows, battery 9, conductor 10, electro-magnet 5, register switch q of rod M^3 , contact spring and its associated contact pin v of key switch M^8 , conductor 12, to battery, and pipe 1'' is sounded, it being of pitch an octave above that of key K' . Operation of key K'' while drawstop M^3 alone is drawn operates key switch M^8 its contact pin v being brought into contact with its associated contact spring which is shown as unconnected in the drawing.
- If drawstop N^3 alone be drawn, operation of key L will cause pipe 1' to sound it being of pitch an octave above that of key L ; and operation of key L' will cause pipe 1'' to sound it being in pitch an octave above that of key L' , the relation of the movable and fixed parts and the circuits being similar to those described above and readily traceable by one skilled in the art.
- 110 Thus the pipes of the first register in their superoctave relation may be sounded by the operation of keys in either or both keyboards.
- If drawstop M^{21} alone be drawn, operation of key K will cause pipe 2' to sound it being of pitch an octave above that of key K ; operation of key K' will cause pipe 2'' to sound it being of pitch an octave above that of key K' .
- If drawstop N^{21} alone be drawn, operation of key L will cause pipe 2' to sound it being of pitch an octave above that of key L .

L; operation of key L' will cause pipe 2" to sound it being of pitch an octave above that of key L'.

Thus the pipes of the second register in 5 their superoctave relation may be sounded by the operation of keys of either or both keyboards.

Thus either or both registers in their superoctave relation may be sounded by the 10 operation of keys of either or both keyboards.

The circuits involved in the above operations are denominated superoctave circuits.

Any of the above described operations 15 may take place simultaneously in all combinations.

While only two registers, and three pipes of each register, and only two keyboards and three keys of each keyboard are shown, 20 the like arrangement of parts and circuits is to be applied to any number of registers and any number of pipes employed in each register and to any number of keyboards within the respective compass of each. 25 While the arrangement is shown for pipes and keys an octave apart any other interval may also be employed. Electrical equivalents, as solenoids for electro-magnets, and mechanical equivalents may also be employed without departing from the spirit of 30 my invention.

I claim:

1. An electric organ-action comprising an electro-magnetic pipe-sounding device for 35 each pipe of a register of pipes, unison, sub-octave, and superoctave circuits, a keyboard, each key thereof controlling by means of said circuits devices respectively in unison, sub-octave, and superoctave pitch relation 40 with said key within the compass of said register, key switches and register switches, a key switch and a register switch being included in each circuit in series, and drawstops controlling the register switches.

2. An electric organ-action comprising an electro-magnetic pipe sounding device for each pipe of a register of pipes, unison, sub-octave, and superoctave circuits, a keyboard, each key thereof controlling by means of 50 said circuits devices respectively in unison, sub-octave, and superoctave pitch relation with said key within the compass of said register, key switches and register switches, a key switch and a register switch being included in each circuit in series, the key switches controlled by a key being a multiple contact switch, and drawstops controlling the register switches.

3. An electric organ-action comprising an 60 electro-magnetic pipe sounding device for each pipe of a register of pipes, unison, sub-octave, and superoctave circuits, a keyboard, each key thereof controlling by means of said circuits devices respectively in unison, sub-octave, and superoctave pitch relation with said key within the compass of said registers, key switches and register switches, a key switch and a register switch being included in each circuit in se-

son, suboctave, and superoctave pitch relation with said key within the compass of said register, a branch circuit for each device controlled by keys respectively in unison, sub-octave, and superoctave pitch relation with said device within the compass of said keyboard, key switches and register switches, a key switch and a register switch being included in each circuit in series, and drawstops controlling the register switches.

4. An electric organ-action comprising an 75 electro-magnetic pipe sounding device for each pipe of a register of pipes, unison, sub-octave, and superoctave circuits, a keyboard, each key thereof controlling by means of said circuits devices respectively in unison, 80 sub-octave, and superoctave pitch relation with said key within the compass of said register, a branch circuit for each device controlled by keys respectively in unison, sub-octave, and superoctave pitch relation 85 with said device within the compass of said keyboard, key switches and register switches, a key switch and a register switch being included in each circuit in series, the key switches controlled by a key being a multiple contact switch, and drawstops controlling 90 the register switches.

5. An electric organ-action comprising an electro-magnetic pipe sounding device for 95 each pipe of a register of pipes, unison, sub- and super circuits, a keyboard, each key thereof controlling by means of said circuits devices respectively in unison, sub-, and super pitch relation with said key within the compass of said register, key switches and register switches, a key switch and a register switch being included in each circuit in series, and drawstops controlling the register switches.

6. An electric organ-action comprising an 105 electro-magnetic pipe-sounding device for each pipe of registers of pipes, unison, sub-octave, and superoctave circuits, a keyboard, each key thereof controlling by means of said circuits devices of each register respectively in unison, suboctave, and superoctave 110 pitch relation with said key within the compass of said registers, key switches and register switches, a key switch and a register switch being included in each circuit in series, and drawstops controlling the register switches.

7. An electric organ-action comprising an electro-magnetic pipe sounding device for each pipe of registers of pipes, unison, sub-octave, and superoctave circuits, a keyboard, each key thereof controlling by means of 120 said circuits devices of each register respectively in unison, suboctave, and superoctave pitch relation with said key within the compass of said registers, key switches and register switches, a key switch and register switch being included in each circuit in se-

ries, the key switches controlled by a key being a multiple contact switch, and draw stops controlling the register switches.

8. An electric organ-action comprising an
5 electro-magnetic pipe sounding device for
each pipe of registers of pipes, unison, sub-
octave and superoctave circuits, a keyboard,
each key thereof controlling by means of
said circuits devices of each register respec-
10 tively in unison, suboctave, and superoctave
pitch relation with said key within the com-
pass of said registers, a branch circuit for
each device controlled by keys respectively
in unison, suboctave, and superoctave pitch
15 relation with said device within the com-
pass of said keyboard, key switches and reg-
ister switches, a key switch and a register
switch being included in each circuit in se-
ries, and drawstops controlling the register
20 switches.

20 switches.

9. An electric organ-action comprising an electro-magnetic pipe sounding device for each pipe of registers of pipes, unison, sub-octave, and superoctave circuits, a keyboard, 25 each key thereof controlling by means of said circuits devices of each register respectively in unison, suboctave, and superoctave pitch relation with said key within the compass of said registers, a branch circuit for 30 each device controlled by keys respectively in unison, suboctave, and superoctave pitch relation with said device within the compass of said keyboard, key switches and register switches, a key switch and a register 35 switch being included in each circuit in series, the key switches controlled by a key being a multiple contact switch, and draw-stops controlling the register switches.

40 10. An electric organ-action comprising an
electro-magnetic pipe sounding device for
each pipe of a register of pipes, unison, sub-
octave, and superoctave circuits, keyboards,
each key thereof controlling by means of
said circuits devices respectively in unison,
45 suboctave, and superoctave pitch relation
with said key within the compass of said
register, key switches and register switches,
a key switch and a register switch being in-
cluded in each circuit in series, and draw-
50 stops controlling the register switches.

50 stops controlling the register switches.

11. An electric organ-action comprising an electro-magnetic pipe sounding device for each pipe of a register of pipes, unison, sub-octave, and superoctave circuits, keyboards,
55 each key thereof controlling by means of said circuits devices respectively in unison, suboctave, and superoctave pitch relation with said key within the compass of said register, key switches and register switches,
60 a key switch and a register switch being included in each circuit in series, the key switches controlled by a key being a multiple contact switch, and drawstops controlling the register switches.

12. An electric organ-action comprising 65
an electro-magnetic pipe sounding device for
each pipe of a register of pipes, unison, sub-
octave, and superoctave circuits, keyboards,
each key thereof controlling by means of said
circuit devices respectively in unison, suboc-
tave, and superoctave pitch relation with
said key within the compass of said register,
a branch circuit for each device controlled
by keys in each keyboard respectively in
unison, suboctave, and superoctave pitch re-
lation with said device within the compass
of said keyboards, key switches and register
switches, a key switch and a register switch
being included in each circuit in series, and
drawstops controlling the register switches. 70

13. An electric organ-action comprising an electro-magnetic pipe sounding device for each pipe of a register of pipes, unison, sub-octave, and superoctave circuits, keyboards, each key thereof controlling by means of said circuits devices respectively in unison, suboctave, and superoctave pitch relation with said key within the compass of said register, a branch circuit for each device controlled by keys in each keyboard respectively in unison, suboctave, and superoctave pitch relation with said device within the compass of said keyboards, key switches and register switches, a key switch and a register switch being included in each circuit in series, the key switch controlled by a key being a multiple contact switch, and draw-stops controlling the register switches. 85 90 95

14. An electric organ-action comprising an electro-magnetic pipe sounding device for each pipe of registers of pipes, unison, sub-octave, and superoctave circuits, keyboards, each key thereof controlling by means of said circuits devices of each register respectively in unison, suboctave, and superoctave pitch relation with said key within the compass of said registers; key switches and register switches, a key switch and a register switch being included in each circuit in series, and drawstops controlling the register switches. 100 105 110

15. An electric organ-action comprising an electro-magnetic pipe sounding device for each pipe of registers of pipes, unison, sub-octave, and superoctave circuits, keyboards, each key thereof controlling by means of said circuits devices of each register respectively in unison, suboctave, and superoctave pitch relation with said key within the compass of said registers, key switches and register switches, a switch key and a register switch being included in each circuit in series, the key switches controlled by a key being a multiple contact switch, and drawstops controlling the register switches. 115 120 125

16. An electric organ-action comprising an electro-magnetic pipe sounding device for each pipe of registers of pipes, unison, sub-

- octave, and superoctave circuits, keyboards, each key thereof controlling by means of said circuits devices of each register respectively in unison, suboctave, and superoctave 5 pitch relation with said key within the compass of said registers, a branch circuit for each device controlled by keys in each keyboard respectively in unison, suboctave, and superoctave pitch relation with said device 10 within the compass of said keyboards, key switches and register switches, a key switch and a register switch being included in each circuit in series, and drawstops controlling the register switches.
- 15 17. An electric organ-action comprising an electro-magnetic pipe sounding device for each pipe of registers of pipes, unison, suboctave, and superoctave circuits, keyboards, each key thereof controlling by means of
- said circuits devices of each register respectively in unison, suboctave, and superoctave 20 pitch relation with said key within the compass of said registers, a branch circuit for each device controlled by keys of each keyboard respectively in unison, suboctave, and 25 superoctave pitch relation with said device within the compass of said keyboards, key switches and register switches, a key switch and a register switch being included in each circuit in series, the key switches controlled 30 by a key being a multiple contact switch, and drawstops controlling the register switches.
